UNITED STATES PATENT OFFICE

IRVING FLORMAN, OF NEW YORK, N. Y.

DESIGN FOR A BEER MUG OR THE LIKE

Application filed March 28, 1933. Serial No. 47,622. Term of patent 14 years.

To all whom it may concern:

Be it known that I, IRVING FLORMAN, a citizen of the United States, residing at New York, in the county of New York and State of New York, have invented a new, original, and ornamental Design for Beer Mugs or the like, of which the following is a specification, reference being had to the accompanying drawing, forming part thereof.

Fig. 1 is a perspective view of the article showing my new design.

Fig. 2 is a fragmentary front elevation of the upper portion, showing particularly the top of the article.

Fig. 3 is a fragmentary side elevation of the upper portion, showing particularly the latch element of the article.

Fig. 4 is a top plan view.

The dominant feature of my design is the top.

I claim:

The ornamental design for a beer mug or the like substantially as shown and described.

IRVING FLORMAN.
